UNITED STATES PATENT OFFICE.

HERBERT H. ROOSA, OF LINCOLN, NEBRASKA.

SHOE-CLAMPING DEVICE.

1,369,936.

Specification of Letters Patent.

Patented Mar. 1, 1921.

Application filed February 13, 1920. Serial No. 358,451.

To all whom it may concern:

Be it known that I, HERBERT H. ROOSA, a citizen of the United States, and resident of Lincoln, in the county of Lancaster and State of Nebraska, have invented certain new and useful Improvements in Shoe-Clamping Devices; and I do hereby declare the following to be a full, clear, and exact description of the same, reference being had to the accompanying drawings, forming a part of this specification, and to the reference-numerals marked thereon.

This invention relates to shoe manufacture and more particularly to apparatus for use in attaching the heel to the shoe, one object of the invention being the provision of a simple, convenient and effective clamp for holding a heel in place on the shoe after it has been cemented or glued and applied thereto.

Another object is to provide a device of the above character applicable to various shapes and sizes of shoes and heels and adapted to adjust itself automatically to the varying pitch and other lines of the heel.

Another object is the provision of a clamp of this nature particularly adapted to firmly and securely engage the heel and to thereby clamp the latter to the shoe with uniformly and effectively applied force.

Another object is to provide, in a device of this character a construction which may be quickly and efficiently operated by unskilled labor. To these and other ends the invention consists in certain improvements and combinations of parts, all as will be herein-after more fully described, the novel features being pointed out in the claims at the end of the specification.

In the drawings:—

Figure 1 is an elevation of a clamping apparatus embodying the present invention.

Fig. 2 is a similar view as seen from the left in Fig. 1.

Fig. 3 is a section on the line 3^a—3^a of Fig. 1.

Similar reference characters throughout the several views indicate the same parts.

In the embodiment at present preferred as best illustrating the principles involved, the invention comprises a last support, or pedestal, 5, having a base 6 adapted to be placed on a work bench or other support and be attached thereto if desired, the pedestal adjacent the base having formed thereon oppositely arranged bosses 7 provided with

bearing openings 8 in which are rotatably supported the inturned ends 9 of a pair of oppositely arranged, spaced guiding elements, or rods, 10, forming part of a clamp carrier 60 indicated generally at 11.

The clamp carrier comprises, in addition to the guide rods 10, a cross bar, or head, 12 connecting the upper ends of the rods. This bar is formed adjacent the center with a 65 threaded opening in which is engaged a correspondingly threaded rod 13, having at its upper end a head 14 carrying a handle 15, by means of which the rod is rotated and thereby advanced or retracted in the head 70 12. The rod is provided at its lower end with a ball 16, closely fitting in a socket 17, formed in a boss 18 on the clamp member 19, a pin 20 being passed through boss 18 just above the ball 16 to secure the latter 75 movably in its socket. This ball and socket joint between the screw rod 13 and clamp 19 affords a flexible connection between the two for a purpose which will be more fully understood hereafter.

Clamp 19 is provided with openings 21 Fig. 3, through which loosely pass the guide rods 10 so that the clamp is readily slideable on the rods toward and from the last support on which is carried a shoe last, such, 85 for example, as that indicated at 22, having a pin 23 received in an opening or bore 24 formed in the top of the pedestal 5. A set screw 25 in the pedestal adjustably secures the last pin in its opening or socket 90 and maintains the last in the desired position. Various styles and sizes of lasts and shoes may be handled in conjunction with the present invention, a shoe 26 being shown in the present instance of the variety having a high French heel 27, the bottom 28 of which has a pitch inclining it to the sole of the shoe, or in other words, the heel bottom is inclined with reference to a plane perpendicular to the general direction of 100 the clamping action. The rear side 29 of the heel is, as usual in this type of shoe, considerably curved as indicated. The underside of clamp 19 is formed with a surface 30 inclined to conform with the pitch 105 of the heel bottom 28 and at the rear of this surface there is provided a shoulder 31 adapted to engage the rear edge of the heel. The clamp bar is thus so shaped as to afford a firm and secure engagement with the bottom of the heel.

Clamp 19 is provided with an extended

portion 32 through which is formed an opening 32^a in which is slidably fitted a part or bar 33 having at its lower end a clamping surface 34 curved to conform with the 5 rear side of the heel. Surface 34 being smoothly curved and extended somewhat to embrace the sides of the heel is thus adapted to securely engage the latter for clamping action in conjunction with the clamping surface 30, without marring the surface or otherwise injuring the heel. The clamping screw 35 is provided, having threaded engagement with an opening in extension 32 of the clamping bar, so as to securely fix 10 15 the part 33 in its adjusted positions.

In the operation of the device, the last is placed on the pedestal 5, and a shoe applied to the last with its heel cemented or glued and properly positioned thereon. The 20 clamp carrier 11, which may be swung downwardly to an out of the way position during the application of the shoe to the last, is then raised above the latter and the handle 15 rotated to bring clamping surface 30 into engagement with the bottom of the heel. The auxiliary clamping part or bar 33 is then adjusted to bear firmly 25 against the rear side of the heel and clamped in adjusted position by means of screw 35, 30 after which the handle 15 may be further turned to press the two clamping surfaces 30 and 34, strongly against the heel. Owing to the close conformation of these clamping surfaces to the shape of the heel the 35 latter is securely engaged and clamped to the sole of the shoe in such a way that the pressure is uniformly applied over the entire surface of engagement between the heel and shoe, and in this way a very considerable 40 pressure may be applied, without danger of injury to the heel or shoe. The flexible connection between the clamp and its actuating rod 13 allows the clamp to automatically adjust itself to the heel and 45 thus further assists in the conformation of the parts. The shoe is then left, subjected to the clamping action, until the cement or glue between the heel and shoe has sufficiently hardened.

50 The clamping part 33 having been once adjusted relatively to the clamping surface 30 for any particular type or size of heel does not require further adjustment for other heels of the same type or dimensions, 55 and the simple and convenient construction of the apparatus permits of the location of successive shoes on the last and the adjustment of the clamp thereto readily and quickly by an unskilled class of labor thus 60 increasing the rate of production and decreasing the manufacturing cost.

I claim as my invention:

1. In a clamping device for shoe heels, the combination with a last support, of a 65 clamp carrier pivotally mounted with refer-

ence to the last support to swing about the same and including spaced guiding elements, and a clamp movable on said elements toward and from the last support and comprising relatively adjustable surfaces for 70 clamping the bottom and side of the heel.

2. In a clamping device for shoe heels, the combination with a last support, of a clamp carrier pivotally mounted with reference to the last support to swing about the 75 same and including oppositely arranged guide rods, and a clamp having bearing portions slidable on said rods toward and from the last support and comprising relatively adjustable clamping surfaces for 80 engaging the bottom and side of the heel.

3. In a clamping device for shoe heels, the combination with a last support, of a clamp carrier pivotally mounted with reference to the last support to swing about the 85 same and including spaced guiding elements, and a clamp movable on said elements toward and from the last support comprising relatively adjustable parts for clamping engagement with the bottom and side of the 90 heel respectively and means for securing said parts in adjusted relation.

4. In a clamping device for shoe heels, the combination with a last support, of a clamp carrier pivotally mounted with reference to the last support to swing about the same and including spaced guiding elements, a clamp movable on said elements toward and from the last support provided with a surface for clamping engagement with the bottom of the heel and also with an aperture, a part slidably carried in said aperture for clamping engagement with the side of the heel, and means for securing said part in 100 adjusted position in said aperture. 105

5. In a clamping device for shoe heels, the combination with a last support, of a clamp carrier comprising a bail-shaped member having spaced guiding elements connected at one end and pivotally connected 110 at the other with said support, and a clamp movable on said guiding elements toward and from said support and comprising relatively adjustable surfaces for clamping engagement with the bottom and sides of the 115 heel.

6. In a clamping device for shoe heels, the combination with a last support, of a clamp carrier pivotally carried with reference to said support to swing about the same and 120 including oppositely arranged guide rods, a clamp slidably engaging said guide rods for movement thereon toward and from the last support comprising a clamping surface inclined with reference to a plane perpendicular to the direction of clamping action to conform to the heel pitch and terminating in a shoulder for engagement with the rear edge of the heel, and a part adjustable on 125 said clamp, having a surface conforming 130

with the rear side of the heel for clamping engagement with the latter.

7. In a clamping device for shoe heels, the combination with a last support having an opening therein, and a last having a pin supported in said opening, of a clamp carrier pivotally mounted with reference to the last support to swing about the latter and including spaced guiding elements, a clamp 5 slidably engaging said elements for movement thereon toward and from the last support, and a part adjustably carried on said clamp having a surface conforming to that of the rear side of the heel for clamping 10 engagement therewith.

8. In a clamping device for shoe heels, the combination with a last support having last receiving means, of a clamp carrier pivotally mounted with reference to said 20 support to swing about the same, a clamp slidable longitudinally of the carrier toward and from said support and having a clamping surface inclined with reference to a plane perpendicular to the direction of 25 clamping action to conform to the heel pitch and terminating in a shoulder positioned for engagement with the edge of the heel, and a part adjustably carried with reference to said clamp having a surface shaped to 30 conform with the rear side of the heel for clamping engagement with the latter.

9. In a clamping device for shoe heels, the combination with a last support, of a clamp carrier pivotally mounted with reference 35 to said support to swing about the latter and comprising spaced guiding elements, a clamp having perforations therein through which said elements pass, said clamp being

slidable on said elements toward and from said support, and a part adjustably carried 40 with reference to said clamp and having a surface shaped to conform to the side of the heel for clamping engagement therewith.

10. In a clamping device for shoe heels, the combination of a last support, a clamp 45 carrier pivotally carried with reference to said support and comprising spaced guiding elements, a head on said carrier, a clamp slidable on said elements comprising relatively adjustable parts for simultaneously 50 clamping the bottom and side of the heel, and means supported on said head for actuating said clamp.

11. In a clamping device for shoe heels, the combination of a last support, a clamp 55 carrier pivotally carried with reference to said support and comprising spaced guiding elements, having a connecting head, a clamp comprising relatively adjustable surfaces inclined to the line of clamping action to 60 conform to the side and the bottom pitch of the heel respectively, and means carried by said head for actuating said clamp.

12. In a clamping device for shoe heels, the combination of a last support, a clamp 65 carrier pivotally carried with reference to said support and comprising spaced guiding elements, having a connecting head, a clamp comprising relatively adjustable surfaces inclined to the line of clamping action to 70 conform to the side and the bottom pitch of the heel respectively, and means carried by said head having a ball and socket connection with said clamp for actuating the latter.

HERBERT H. ROOSA.
